[57] CLAIM

The ornamental design for a tissue dispensing teddy bear, as
shown and described.

DESCRIPTION

FIG. 1 is a front elevational view of a tissue dispensing teddy
bear of the present invention;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear perspective view thereof, with the rear flap
in an opened position.The broken line representation of tissue is for illustrative
purposes only and forms no part of the claimed design.
